UNITED STATES PATENT OFFICE.

THOMAS I. DUFFY, OF CHICAGO, ILLINOIS, ASSIGNOR TO STEWART-WARNER SPEEDOMETER CORPORATION, OF CHICAGO, ILLINOIS, A CORPORATION OF VIRGINIA.

LAMP.

Specification of Letters Patent. Patented June 3, 1919.

1,305,258.

Application filed January 15, 1917. Serial No. 142,402.

To all whom it may concern:

Be it known that I, THOMAS I. DUFFY, a citizen of the United States, residing at Chicago, in the county of Cook and State of Illinois, have invented certain Improvements in Lamps; and I do hereby declare that the following is a full, clear, and exact description thereof, reference being had to the accompanying drawings, and to the characters of reference marked thereon, which form a part of this specification.

This invention relates to improvements in lamps of the type commonly employed for automobile headlights or spot lights. It consists in the elements and features of construction shown and described, as indicated in the claims.

In the drawings:

Figure 1 is a partial vertical section and partial elevation of the lamp.

Fig. 2 is a partial horizontal section and partial elevation of the lamp.

Fig. 3 is a rear elevation of a portion of the reflector and lamp socket.

Fig. 4 is a detail section at the line 4—4 of Fig. 3.

Fig. 5 is a detail section at the line 5—5 of Fig. 4.

Fig. 6 is a perspective view of a spring pawl for locking the adjustable lamp focusing stop.

As shown in the drawings, 10 designates the lamp body or casing which comprises a relatively narrow or shallow sheet metal ring like shell which is open at its rear end and is provided at its front end with an integral or solid lens supporting flange 11. 12 designates a lens which closes the front of the casing, with its marginal portion fitted against and in rear of said flange. A water and dust proof joint is provided between the lens and casing by means of a grooved glazing ring 14, which encircles the lens and fits closely against the inner wall of the casing in rear of said flange 11. 15 designates the reflector, the forward open side of which is provided with a radial, annular flange 16

that bears against the rear side of the glazing ring 14 and is provided with a back turned, cylindrical flange 17 which fits 50 closely against the inner surface of the cylindrical shell 10. The said reflector is held from rotation in the casing by means of a short locking lug 18 extending inwardly from the casing wall and entering a notch 19 formed 55 in the flange of the reflector.

The said glazing ring 14 is made of a suitable soft material, such as lead, which will deform under pressure and is furthermore made slightly oversize, or of greater external 60 diameter than the internal diameter of the casing, so that when the lens and ring are pressed into place within the casing said ring shapes itself to said wall to produce a close or water and dust proof joint between 65 said parts. Moreover the reflector flange 16 is pressed against the rear face of said glazing ring so providing between the reflector and glazing ring a water and dust proof joint. Preferably the surfaces of said glazing ring which engage the casing and reflector are grooved or corrugated so as to insure effective deformation under pressure and, therefore, reliable moisture and dust proof joints between the engaging parts. 70

The rear end of the lamp casing is closed by a removable back plate or wall 20, which is provided with an annular flange 21 that fits the open rear end of the shell in telescopic relation and is detachably locked 80 thereto, as by a bayonet joint 22. Said back plate is formed with a central opening surrounded by a rearwardly directed integral annular projection 24, which constitutes a mounting for a reducing mirror 25 that faces 85 in a direction opposite to the lens 12. The said projection 24 is provided with an annular mirror supporting flange 26. Said mirror is held or pressed against its supporting flange by means of a backing plate 27 90 which is provided with a marginal annular flange 28 that fits closely within the hollow projection 24 and a U-shaped spring 30, the central part of which is attached to said

backing plate and the arms 31 of which are terminally curved at 32 to bear against the convex side of the reflector 15.

5 The coöperation of the spring 30 of the mirror backing plate 27 with the reflector 15, which latter bears against the glazing ring of the lens, is an important feature of construction inasmuch as the action and reaction of the same spring element serves the multiple duty of holding the lens, the reflector and the reducing mirror reliably in place in the assembled lamp structure without the necessity of detachable fastening means. Furthermore it will be observed that the 10 mounting for the reducing mirror is an integral part of the lamp casing, being made an integral part of the back plate of the lamp casing.

At this point it will be noted that by reason of the integral or solid lens supporting flange 11 of the lamp casing, and of the open back of the said casing shell 10, which open back is of a diameter at least as large as the lens glazing ring 14 and as the radial flange 25 16 of the reflector 15, the assembling of the elements of the lamp structure may be effected through the back of the case when the back plate 20 is removed, and that when the lens and reflector are assembled in the 30 casing, and when the mirror 25 and backing plate 27 are assembled in the back plate and the said plate closed upon the casing and locked thereto by the bayonet joint described, or other equivalent locking joint, 35 the spring 30 by its action against the reflector and lens mounting, and its reaction against the backing plate and the mirror serves to reliably hold said parts in assembled position, without the necessity of other 40 locking or holding means. This construction also greatly simplifies and facilitates the assembling operation.

The base of the lamp bulb 35 is provided with the usual pins, which engage bayonet 45 slots that are formed in a socket which is disposed at the back of and concentrically with respect to the reflector 15. Said lamp socket is made as follows:

40 designates an integral, rearwardly directed, concentrically disposed tubular extension or flange of the sheet metal reflector. 41 designates a hollow insulating block at the rear of the reflector into the bore of which extends the flange 40. The 55 said bore of the block 41 is provided with sockets to receive lugs 43 pressed outwardly from the reflector flange, whereby the block is fixed to the reflector.

44 designates a lamp supporting sleeve 60 which fits closely in the bore of said flange 40 and is longitudinally slid able therein. The said sleeve is made of any suitable insulating material desirable. It is provided

with the usual angular sockets 45 to receive the locking pins of the lamp base. The 65 block, 41, is provided with resilient back terminals 46, 47 attached to the block by the screws 100, as shown, and said terminals are located in grooves in the block, and extend at their inner ends toward the axis of the 70 sleeve 44 and through elongated openings 48 in said sleeve. The rear end of the sleeve is screw threaded to receive an adjusting stop nut 50, which nut bears against the rear end face of the block. Said nut is 75 out of contact with the terminals 46 and 47, and, if desired it and the sleeve may be made of an insulating material. The extension of the terminals 46, 47 through the slots in the sleeve 44 holds the sleeve from rotation when 80 the nut 50 is turned on the sleeve, for a purpose hereinafter to be described.

The nut 50 is locked from turning by means of a pawl 55 which engages peripheral notches in said nut. Said pawl may be made 85 integral with a member 56, which is integral with a plate 52, said member, being turned backwardly on said plate 52 to give suitable resiliency for the pawl bearing member, and the plate 52 is apertured to permit 90 the pawl 55 to pass therethrough. The said member 56 is provided with openings 57 so located and dimensioned to allow the passage therethrough of screws by which the locking plate is held in place. The peripheral notches of the nut 50 are of such size and shape as to permit the pawl to ride thereover when the nut is turned, but such as to normally hold the nut from turning.

The spring terminals 46, 47 are of such 100 strength that they act on the lamp plug 34 and therethrough on the sleeve 44 so as to hold the sleeve and the lamp carried thereby at a limit of axial movement, determined by the nut 50 acting against the rear end of the 105 block 41 and said sleeve with its supported lamp is held in a focal adjustment relatively to the reflector by the coöperative action of the spring terminals and said nut. In other words, the spring terminals are the active 110 factors in holding the lamp in a given focal adjustment and the nut 50, operating through one side of its threads only, serves to retract the sleeve 44 and the lamp carried thereby against the action of said springs. 115 Further the nut 50 serves, passively, as a stop, and an adjustable stop by reason of its screw threaded or other adjustable relation to the sleeve 44; and the pawl 55, acting against said nut, serves to lock the parts in 120 adjusted positions. The construction described provides means to adjust the lamp accurately in focal position relatively to the reflector so that lamp bulbs having varying lengths of filaments may be employed in the 125 lamp; and this construction provides means

also whereby the lamp may be adjusted out of focal position when a diffused light is desired.

One of the circuit wires is attached directly to the terminal spring 46, and the other circuit wire is attached at 58 to a swinging switch 59 which has a contact arm or lug 60, which, by swinging movement of the switch, passes into and out of contact with the spring terminal 47. Said switch is guided in its swinging movement by means of a headed screw or pin 62, which extends through a transverse slot of the switch lever. The switch lever extends radially outwardly through an opening 64 of the mirror mounting extension of the back plate and is provided exterior to the casing with a hand piece 65. The circuit wires pass into the casing to the terminal thus described through a bushing 66 which is fixed in any suitable manner in the ring-like shell of said casing.

A feature of importance of the construction described lies in making the principal part of the lamp casing of the ring-like shell 10 provided with a front solid or integral lens supporting flange and open at its rear end. One advantage of this construction is that it simplifies the assembling of the lens and its glazing ring in the lamp casing and enables a dust and water proof joint to be made between the casing and lens without the use of separately formed attaching parts, as screws, locking rings and the like. Furthermore said construction renders available a maximum reflector area, the light transmitting area of the lens being that due to substantially the full diameter of the lens. A further advantage of the construction described is that the main member 10 of the casing may be made sufficiently heavy to form thereon integral bosses or lugs by which to attach the lamp casing to its mounting, while the remaining portion of the casing may be made of substantially lighter material. Therefore, regardless of the size of the lamp casing it will be unnecessary to rivet or braze separately formed attaching lugs to the casing to produce a strong and durable mounting.

Another feature of importance of the construction described lies in the arrangement of the spring 30, or analogous yielding element, whereby its force is employed to hold the lamp elements in place without other detachable fastening means, and whereby also the reducing mirror may be assembled in the lamp structure in a very simple and inexpensive manner. Furthermore this feature of the invention greatly simplifies the construction, lessens its cost and facilitates its assembly.

It is to be understood that the invention

may assume other specific embodiments within the broader phases thereof, as set out in the appended claims, and that the invention is not limited to the embodiment shown except as to such claims where the same is specifically pointed out.

I claim as my invention:

1. A lamp comprising a shell open at its back and provided at its front with a lens supporting flange, a lens fitted against said flange, a glazing ring encircling the lens and engaging the shell wall, a reflector within the casing and bearing at its front end against said glazing ring, interlocking connections between the reflector and shell to prevent rotation of the latter on its axis, a back plate detachably fitted to the shell and means between said back plate and reflector acting to press the latter forwardly against the glazing ring.

2. A lamp comprising a shell open at its back and provided at its front with a lens supporting flange, a lens fitted against said flange, a glazing ring encircling the lens and engaging the shell wall, a reflector within the casing and provided at its front end with a radial flange which bears against said ring and with a back turned flange which engages the casing wall, a back plate detachably fitted to the shell and means interposed between said back plate and reflector to press the reflector forwardly against the glazing ring and to hold the lens against said flange.

3. A lamp comprising a shell open at its back and provided at its front with a lens supporting flange, a lens fitted against said flange, a glazing ring encircling said lens and engaging the shell wall, a reflector bearing at its front end against said ring, a back plate detachably fitted to said shell and a U-shaped spring carried by said back plate with its arms bearing against the back of said reflector.

4. A lamp comprising a casing open at its back, a front lens, a reflector in rear of the lens, a back plate detachably fitted to the casing and provided with an opening surrounded by a mirror supporting flange, a mirror seated within said flange and resilient means interposed between said reflector and said mirror to hold the latter pressed against said flange.

5. A lamp comprising a shell open at its back and provided with a front lens supporting flange, a lens seated against said flange, a back plate detachably fitted to the shell and provided with a mirror supporting flange, a rearwardly facing mirror within said flange and yielding means acting against said mirror and said lens to hold them against their respective flanges.

6. A lamp comprising a shell open at its

- back, and provided with a front lens supporting flange, a lens seated against said flange, a glazing ring encircling said lens, a reflector in rear of the lens bearing against said ring, a back plate detachably fitted to said shell and provided with a mirror supporting flange, a rearwardly facing mirror within said flange and a spring interposed between said mirror and the reflector.
10. 7. In a lamp, the combination with a reflector provided with a rearwardly directed tubular flange, of a hollow insulating base applied over said flange and interlocked thereto to fasten the base to the reflector, and spring lamp terminals attached to said base and extending radially across the bore of said hollow base.
8. A lamp provided with a front lens, a rearwardly facing mirror, and means interposed between and acting against said lens and mirror to hold them in place.
20. 9. A lamp provided with a front lens, a rearwardly facing mirror and a single resilient member exerting pressure on the lens and mirror to hold them in place.
25. 10. A lamp comprising a casing provided with a front lens supporting flange and open at its back, with the diameter of the back opening equal at least to that of said flange, a back plate detachably fitted to the casing, a mirror mounting carried by said back plate and a mirror supported by said mounting.
30. 11. In a lamp, combination with a reflector and its tubular flange, of a hollow insulating block applied over said flange and locked thereto and provided with spring terminals, a lamp supporting sleeve within and adjustable lengthwise of said flange, and adjustable means coöperating with said spring terminals to axially adjust said sleeve and hold it in adjustable positions.
35. 12. In a lamp, the combination with a reflector, a lamp supporting sleeve disposed axially of the reflector, a lamp bulb supported by and locked in said sleeve, spring terminals bearing against the base of the lamp bulb and means acting against said spring terminals to limit the focal adjustment of the bulb in the reflector.
40. 13. In a lamp, the combination with a reflector, a lamp supporting sleeve disposed axially of the reflector, a lamp bulb supported and locked in said sleeve, spring terminals bearing against the base of the lamp bulb and means acting against said spring terminals to limit the focal adjustment of the bulb in the reflector, with means to lock the sleeve in adjusted positions.
45. 14. In a lamp, the combination with a reflector and a hollow insulating block secured axially thereto, of a lamp bulb supporting sleeve movable axially in said block, a stop nut threaded to said sleeve and bearing against said block and spring means acting
50. against said sleeve to adjust the sleeve axially in said block.
15. In a lamp, the combination with a reflector and a hollow insulating block secured axially thereto, of a lamp supporting sleeve movable axially in said block, a nut threaded to said sleeve and bearing against the block, and spring terminals for contact with the lamp bulb base and coöperating with said nut to obtain focal adjustment of the bulb.
55. 16. In a lamp, the combination with a reflector and a hollow insulating base secured axially thereto, of a lamp bulb supporting member movable axially in said block, resilient means carried by said block to act against the base of a bulb seated in said member to hold the bulb in adjusted positions in the reflector relatively to its focal plane, and an adjustable limiting stop co-operating with said resilient means.
60. 17. In a lamp, the combination with a reflector and a hollow insulating base secured axially thereto, of a lamp bulb supporting member movable axially in said block, fixed spring lamp terminals mounted in the block and extending radially toward the axis of the block for engagement with the terminals of the base of a lamp bulb carried by said supporting member, and an adjustable limiting stop acting on said supporting member.
65. 18. In a lamp, the combination with a reflector and a hollow insulating block secured axially thereto, of a lamp bulb supporting member movable axially in said block, fixed spring lamp terminals mounted on the block and extending radially toward the axis of the block for engagement with the terminals of the base of a lamp bulb carried by said supporting member, and an adjustable stop carried by said supporting member and acting against said block in opposition to the action of said spring terminals.
70. 19. In a lamp, the combination with a reflector and a hollow insulating block secured axially thereto, of a lamp bulb supporting member movable axially in said block, fixed spring lamp terminals mounted on the block and extending radially toward the axis of the block for engagement with the terminals of lamp base and interlocked to the supporting member to hold it from rotation, and a nut threaded to the supporting member and bearing against said block.
75. 20. In a lamp, the combination with a reflector and a hollow insulating block secured axially thereto, and provided with radially disposed terminal springs to engage a lamp base, of a lamp supporting sleeve movable axially in said block, a nut threaded to said sleeve and coöperating through said sleeve and a contained lamp base to vary the focal position of a lamp in the reflector, and a locking pawl to engage and lock said nut.
80. 21. In a lamp, the combination with a re-

5 flector and a hollow insulating block secured axially thereto, of a lamp supporting sleeve movable axially in said block, a nut threaded to said sleeve and bearing against said block and resilient lamp terminals secured to the block and extending radially inwardly across the bore of the block and through slots in said sleeve.

In witness whereof I claim the foregoing

as my invention, I hereunto append my signature in the presence of two witnesses at Chicago, Illinois, this 18th day of October, 1916.

THOMAS I. DUFFY.
